UNITED STATES PATENT OFFICE.

WILLIAM J. BAYRER, OF SOUTHBURG, CONNECTICUT, ASSIGNOR TO THE PECK, STOW & WILCOX COMPANY, OF SAME PLACE.

MACHINE FOR FOLDING SHEET METAL.

SPECIFICATION forming part of Letters Patent No. 314,311, dated March 24, 1885.

Application filed December 18, 1884. (No model.)

To all whom it may concern:

Be it known that I, WILLIAM J. BAYRER, a citizen of the United States, residing at Southbury, in the county of Hartford and State of

5 Connecticut, have invented certain new and useful Improvements in Machines for Folding Sheet Metal, of which the following is a specification.

My invention is an improvement upon the folder patented to O. W. Stow, February 28, 1860, No. 27,319; and the objects of my improvement are to facilitate the manufacture of the machine, to enable one part thereof when worn to be duplicated at a small expense, and 15 to positively lock the gage in position when desired.

In the accompanying drawings, Figure 1 is a plan view of my sheet-metal-folding machine. Fig. 2 is a front elevation. Fig. 3 is a side elevation. Fig. 4 is a partial section thereof on line *x x* of Fig. 1. Fig. 5 is another partial section thereof on line *y y* of Fig. 1, and Fig. 6 is a front elevation of a portion of the slide which moves the gage.

25 The main portion of the machine need not be described in detail, because it is substantially the same as has heretofore been manufactured under the said patent to Stow.

A designates the folding-bar, which turns in 30 the bearings *a*, which bearings are mounted upon the swinging frame *b*. This bar is moved by means of the lever *B*.

C designates the plate, around the edge of which the folding-bar turns, and D designates 35 the gage underneath the plate C, for regulating the width of the lock to be turned. In the prior machines this gage was moved by the direct action of a screw located in the frame at about the middle of its length. I 40 provide this gage D with two wings having oblique slots *d*. In Fig. 1 a part of the plate C is broken away and removed, so as to better show the other parts. One end of this gage is shown in full lines in this figure, while 45 the contour of its opposite end is indicated by broken lines.

Underneath the gage D, and lying in a longitudinal groove through the frame E, is the gage-slide *f*, Figs. 1, 4, and 6, which slide is 50 provided with projections or lugs *g*, which are received by the oblique slots *d* in the gage.

The end of this gage-slide *f* is bored and threaded to receive a left-hand screw, and in the frame is a nut, *h*, which is threaded to receive a right-hand screw.

55

F designates the gage-adjusting screw, which screw is provided with a right and left hand portion, to fit the nut *h* and end of slide *f*, respectively, as shown most clearly in Fig. 1. The slide *f* having lugs which engage the oblique slots in the gage D, the screw F and its nut *h* constitute the gage-adjusting mechanism in its improved form. In said Fig. 1 the gage is represented as thrown forward to its extreme limit. By turning the gage-screw F in 60 a left-handed direction the gage-slide *f* will be moved to the right, and thereby draw the gage D back away from the edge of the plate. The gage-slide lies within a longitudinal groove within the frame, which is milled out so that 65 the slide may be neatly fitted thereto. For the purpose of saving labor in fitting the slide, portions of its sides are cut away, as shown in Fig. 1, care being taken, however, to leave a bearing-surface of some length, which will 70 bear closely against the wall of the groove near the middle of the length of the frame, and upon that side which is nearest the folding-bar.

75

When a large job of work of a particular 80 style is to be done, it sometimes happens, especially when the machine is much worn, that the position of the gage may change a little from the position to which it was left by the gage-adjusting screw. In order to prevent 85 such an accident I provide the machine with means, in addition to the gage-adjusting screw, for locking the gage-slide against movement in either direction. This means, in the present instance, consists in a simple set-screw, *k*, in 90 such a position as to press upon the gage-slide near the middle of its length and bind it firmly against the opposite wall of the groove in which it slides whenever it is desired to hold it in position with greater positiveness 95 than it would be held by the gage-adjusting screw alone. The set-screw of course must be loosened or turned back preparatory to adjusting the gage to a different position.

The nut *h* for the adjusting-screw is a part 100 which is subject to great wear. In order that this nut when worn may be duplicated or re-

newed without removing the entire frame of the machine, I have made this nut so that it is readily attachable and detachable. By so doing I am also enabled, when the nut is removed, to leave the groove for the gage-slide *f* open from end to end of the frame *E*, whereby a milling-tool may be run through the groove, so that it can be milled much more conveniently and at less expense than could be the case provided the nut were an integral part of the frame. I secure this nut, which is formed separately from the frame *E*, in place by means of the tenon *m*, Fig. 5, which fits into a hole in the frame underneath the body of the nut, while the plate *C*, which is held upon the frame by screws in the ordinary manner, bears upon the top of the nut in such manner as to prevent it from working up out of place. By removing this plate the nut can be readily taken out and a new one substituted therefor at a trivial cost.

I have shown and described the oblique slots in the gage and the studs on the gage-slide as means for operatively connecting said parts. Other means which will cause the

gage to move back and forth upon a longitudinal movement of the gage-slide I consider the equivalent of said slots and studs.

I claim as my invention—

1. In a machine for folding sheet metal, the combination of the gage *D*, the gage-adjusting mechanism for moving said gage, and means, in addition to the adjusting mechanism, for locking said gage against movement in either direction, substantially as described, and for the purpose specified.

2. In a machine for folding sheet metal, the combination of the frame, the gage *D*, mounted thereon, and having the oblique slots, the gage-slide *f*, having the studs which enter said oblique slots and move longitudinally within a groove in the frame, the gage-adjusting screw *F*, and the nut *h*, formed separately from the frame *E*, substantially as described, and for the purpose specified.

WILLIAM J. BAYRER.
